UNITED STATES PATENT OFFICE

GEORGE J. KATZ, OF ST. PAUL, MINNESOTA

AUTOMATIC STOP

Application filed June 24, 1929. Serial No. 373,081.

My invention relates to an automatic electrical stop for envelope machines, designed to be associated particularly with the envelope folding mechanism so that if for any reason the machine which forms the envelope shall fail to register in the folding compartment when the plunger operates in the plunger type of envelope machine, a circuit will be closed and this will operate a release which releases the clutch so that it will stop the envelope machine immediately.

A feature of the invention resides in the simplicity of the structure which is designed to operate to close the circuit whenever an envelope sheet is misplaced or torn or out of registry with the plates which close the sides of the same in as the plunger of the envelope machine operates to fold the envelope.

A feature of my invention resides in providing a circuit closing pin associated with one or more of the folding plates of the envelope machine which folds the flaps of the envelope inward when the plunger pushes the envelope down into the folding compartment. If the envelope folds properly and passes on through the folding compartment, no contact will be made and the machine continues to operate to fold the envelopes rapidly. This type of envelope folding machine operates very rapidly and as the sheet is picked up off of the pile of flat sheets which have been died out to the shape of the envelope and these sheets are passed over to the plunger, it is pushed down into the folding compartment by the plunger means and the side plates fold in the end flaps of the envelope so as to fold the same down into place so that they can be stuck together to form the envelope in the forming compartment. If the sheet forming the envelope is out of place or tears and clogs up the machine or is out of registry, then the circuit closing plug will contact with the portion of the machine which is grounded so that a circuit is made to close the circuit to operate the catch which releases the clutch of the machine, thereby immediately stopping the same. It is important in my invention to provide an electrical means for stopping the envelope folding machine or forming machine quickly and

at a time when the trouble occurs. This is usually apparent at the folding of the envelope or for lack of the folding mechanism to receive an envelope sheet to be folded or from the tearing of the sheet in the operation of the machine or when it is out of registry. Any of these causes will immediately operate my electric stop by closing the circuit and stop the machine almost instantaneously.

These features together with other details and objects of my invention will be more fully and clearly set forth in the specification and claims.

Figure 1 is a diagrammatic side view of a portion of an envelope folding machine of the plunger type, showing my electric stop applied to the same.

Figure 2 is a plan view of a detail showing the parts enlarged looking down into the folding compartment and showing the side plate which operates inwardly to fold the ends of the envelope inward in the operation of the envelope folding machine.

Figure 3 is an enlarged detail of a portion of the envelope folding machine showing my circuit closing switch plug.

Figure 4 is a further detail similar to Figure 3, showing the parts in a different position with the side plate down against the bottom plate of the folding pocket of the envelope machine.

Figure 5 is a diagrammatic view showing the wiring of my electric stop for envelope folding machines.

Figure 6 is a detail of a portion of the envelope folding machine showing the means of operating the clutch from the front.

Figure 7 is a plan detail of the side of the envelope folding machine showing the lever which operates the clutch of the machine associated with the operating belt and pulley.

In the drawing I have illustrated a portion diagrammatically of an envelope folding machine of the plunger type such as A, which shows the shaft 10 which supports the lifter members 11 of the envelope folding machine. These lifter members function to place the glue upon the sheets 12 which are illustrated in a pile B arranged directly below the lifter members 11. The plate 13 directly above the

pile B is a clearing plate which clears the sheet off of the lifter members 11.

In the operation of the lifter members, these members are operated up and down 5 and go down against the top sheet 12 in the pile B and lift it upward so that it can be separated from the rest of the sheets and then by suitable mechanism not illustrated, the sheet is carried back above the folding 10 pocket C which is directly adjacent the lifters 11 and the pile B.

When the sheet is positioned above the folding pocket C the plunger 14 which is carried by the shaft 15 is operated to push 15 the sheet into the folding pocket and as the sheet passes into the folding pocket, the side or end plates 16 and 17 are operated to fold the flaps of the envelope down against the bottom 18 of the pocket C.

Upon the side folding plate 16, I provide 20 a switch pin 19 which is insulated from the plate 16 by the insulating medium 20 and which passes through the hole 21 in the plate 16 in a manner so that the pin 19 will not 25 contact with the plate 16 at any place to cause a short circuit. This pin 19 is of a spring nature so that when the pin strikes the bottom plate 18, it will recede into the insulating medium 20 as illustrated in Figure 4. The 30 pin 19 is held by the spring 22 in operative position so that it can slide back when the plate 16 is in the position illustrated in Figure 4. The pin 19 is connected by the slideable arm 23 which is slidably supported at 35 42 which also insulates the arm 23 and this arm is connected by means of the wire 24 to the operating solenoid 25. I provide a suitable switch 26 in the wire 24 so that the same can be turned off when it is desired. The solenoid 40 is grounded on one side by the wire 26 to the frame of the machine A. It will also be noted that a suitable ground such as 27 is illustrated for the plate 18 of the machine A so as to illustrate the electric circuit which is 45 completed when the stop is operated.

The diagrammatic illustration shows a 50 source of electric energy such as D and obviously the circuit may be operated by any suitable source of electric energy to operate the electric stop which stops the automatic envelope folding machine A. In the circuits illustrated in Figure 5, I show a switch 28 connected by the lead wire 29 to a ground so that the solenoid 25 may be operated separately 55 from the switch pin 19 to operate the solenoid 25 so as to stop the envelope folding machine A independently of the automatic electric stop as will be hereinafter described.

The envelope machine A is provided with 60 an operating clutch E illustrated in Figure 7 which is operated by the lever 30 which connects the clutch E to be driven by the belt 31. The clutch and belt with the pulley and drive 65 shaft 32 are of ordinary construction and

are not illustrated in detail but just diagrammatically in the drawing.

The lever 30 is held by a suitable catch 70 33 also illustrated diagrammatically and which is operated by the solenoid 25 so that when a circuit is closed to operate the solenoid 25, the catch 33 will be operated and by means of a spring 36 the clutch lever 30 is operated into the position illustrated in dotted outline in Figure 7 releasing the 75 clutch E and immediately stopping the operation of the envelope machine A. The free end of the lever 30 is supported on the bracket shelf 37 which is supported by the bracket arms 38 projecting outwardly from 80 the side of the frame 39 of the envelope folding machine A.

In operation the envelope folding machine 85 operates very rapidly and is all automatic in the operation of folding the envelope. The sheets 12 which have been dried out to the formation of the envelope are placed in the pile B below the lifting members 11 and these members pass down through the clearing plate 13 and having glue on their under surface, they pick up a sheet and lift it up to the clearing plate 13 and then by suitable mechanism not illustrated, the sheet is carried back to the plunger 14 which pushes it down into the folding pocket C. As the sheet is pushed down 90 into this folding pocket, the side or end plates 16 and 17 operate inwardly to fold the flaps of the envelope in and seal the same together so as to form the envelope, all of which operation is very rapid and the envelope is carried 95 on by other suitable mechanism not illustrated in which it is held until it has dried sufficiently to hold the envelope together.

My electric stop operates to prevent waste 100 of the envelope sheets and to stop the automatic envelope machine A before it has spoiled a large number of sheets and particularly to assist the operator in the operation of the automatic envelope machine A. In fact, with 105 my electric stop, one operator can run several automatic envelope folding machines such as A for the reason that the electric stop operated by the folding plate 16 will operate instantly to disengage the operating clutch E and stop the automatic envelope folding machine if for any reason the sheets 12 do not 110 properly register in the folding compartment C.

The operation of my electric stop is very 115 simple in that the pin 19 will contact with the plate 18 if the paper sheet 12 of the envelope is not between the folding plate 16 and the bottom 18. Thus, the circuit will be closed as illustrated in the diagrammatic illustration of the circuit in Figure 5 and the 120 solenoid 25 will be operated to release the catch 33 which will cause the spring 36 to operate the lever 30 releasing the clutch E and stopping the envelope machine virtually 125 instantaneously.

It is very important in my machine to provide an electric stop in the proper position in the machine and for this reason I have found that my electric stop operable with the folding plate 16 is a most practical means of controlling the operation of the automatic envelope folding machine A. It will be noted that the folding plate 16 is at a vital point of operation of the envelope folding machine A and it is at this place where the trouble if any usually occurs, either a sheet is torn or does not register and then my automatic stop operates by the pin 19 which closes the circuit immediately, my automatic electric stop stopping the machine virtually instantaneously right at the vital moment when the sheet either does not register in the folding pocket or becomes torn so as to prevent the same from passing through the folding operation properly.

The plate 16 which carries the operating switch pin 19 is operated by the usual operating lever 43 of the envelope folding machine A only a portion of the lever 43 being illustrated. The plate 17 is operated by a similar lever. The arm 23 slides slightly to compensate for the movement of the hinge plate 16 so that the operation of the plate 16 is not changed and the arm 23 acts as a rigid cable to carry the current back away from the operating parts of the folding mechanism which might otherwise interfere with the free operation of these parts.

The saving in labor and waste of material is so apparent in the use of my electric stop for the plunger type of envelope folding machines that I have found it practical for one operator to operate quite a number of these machines without danger of any material waste in the operation of the same. The operator is quickly apprised of the stopping of any of the machines and by means of the switch 26, my electric stop may be thrown out of operation until it is again started on its way to properly folding and finishing the envelopes.

In accordance with the patent statutes I have described the principles of my electric stop for the plunger type of automatic envelope folding machines and while I have illustrated a particular formation and design, I desire to have it understood that the same is only suggestive of a means of carrying out my invention and I desire to protect the same within the scope of the following claims.

I claim:

1. An electric stop for plunger automatic envelope folding machines including a folding plate, a circuit closing spring pin carried by the folding plate which is adapted to close a circuit through a ground when a sheet fails to come to rest in the proper position in the folding compartment, a solenoid operable by said circuit closing pin to release a clutch operating lever to stop said envelope folding machine.

2. An electric stop for envelope folding machines including, a circuit closing pin pivotally supported in a manner to be operated by the flap folding portion of the envelope folding machine, a solenoid in circuit with said circuit closing pin, a catch adapted to be operated by said solenoid, a clutch lever adapted to be held in operative position by said catch and a spring for pulling said lever out of operating position to automatically stop the automatic envelope folding machine. 70

3. An automatic electric stop for envelope folding machines, including, a movable spring circuit closing pin, a folding plate adapted to carry said pin and electric circuit means operable by the grounding of said pin to form a circuit to release the operating clutch of the envelope folding machine and stop the same. 80

4. An electric stop for plunger type automatic envelope folding machines including, a folding plate for folding the flaps of the envelope in forming the same, a circuit closing pin carried by and insulated from said plate, circuit and solenoid means connected with said pin in a manner to operate to release the operating clutch of said envelope folding machine when said circuit closing pin is grounded through the absence of an envelope between the plate and the frame of 95 the machine. 85

5. An electric stop for automatic envelope folding machines including, a folding plate, a bottom plate against which the envelopes are folded, a circuit closing pin carried by said plate and insulated therefrom, spring means for operating a clutch lever out of operating position, a catch for holding said clutch lever and circuit and solenoid means associated with said circuit closing pin to operate the same when the pin is grounded against said bottom plate by the absence of an envelope sheet between the folding plate and the bottom plate. 100 105

6. An electric stop for automatic envelope folding machines including, a folding plate, a switch pin carried by said plate, circuit closing means carried by said folding plate and means associated with said pin carried by said plate to release said operating lever 110 and thereby release the clutch which operates the automatic envelope folding machine. 115

7. An electric stop for envelope folding machines of the plunger type including, a folding pocket, a folding plate pivotally secured to the sides of said pocket and means for operating said plate to carry the same down to the bottom of said pocket and circuit closing means to operate the clutch of said envelope machine carried by said folding plate in said pocket operable in the absence of an envelope in said pocket by grounding the circuit. 120 125

8. An electric stop for automatic envelope folding machines including, a switch pin, a 130

flap folding plate adapted to support said pin insulated therefrom, a slidable cable arm for carrying current from said pin, a circuit leading from said cable arm to a switch and to an operative solenoid and catch means operable by said solenoid to release the clutch of said envelope folding machine.

9. An electric stop for automatic envelope folding machines including, hinged plate means for folding the flaps of the envelope, electric switch means carried by said folding plate, solenoid means and electric circuit means associated with said switch in a manner to stop said automatic envelope folding machine in the absence of an envelope sheet beneath said plate carrying said switch.

10. An electric stop for automatic envelope folding machines including, an intermittently operable switch means carried by one of the folding parts of the envelope machine, an electric circuit connected with said switch, a clutch for stopping said envelope machine and means in said circuit for operating said clutch to release the same and automatically stop said envelope folding machine when said switch is operated by the absence of an envelope sheet beneath said folding part which carries said switch.

11. An electric stop for automatic envelope folding machines including, an intermittently operable circuit closing switch adapted to be operated by grounding by contacting with a portion of said machine, an electric circuit closed by said switch when the same is grounded, means in said circuit for operating the clutch to stop said envelope folding machine when said circuit is closed by said switch, said switch being carried by a portion of said envelope folding machine which is adapted to complete the folding operation of the envelopes and the switch being inoperative through the insulating properties of the envelope sheet.

GEORGE J. KATZ.
